UNITED STATES PATENT OFFICE.

JAMES HOULEHAN, OF TOLEDO, OHIO, ASSIGNOR TO GEORGE G. HADLEY
AND GEORGE P. MERRILL, BOTH OF SAME PLACE.

WRENCH.

SPECIFICATION forming part of Letters Patent No. 289,847, dated November 27, 1883.

Application filed October 26, 1883. (No model.)

To all whom it may concern:

Be it known that I, JAMES HOULEHAN, of Toledo, in the county of Lucas and State of Ohio, have invented certain new and useful 5 Improvements in Wrenches, of which the following is a specification, reference being had to the accompanying drawings, and to the letters of reference marked thereon.

This invention has reference to that class of 10 wrenches known as "monkey-wrenches," wherein one jaw of the wrench is fixed and the other capable of adjustment.

The invention consists in the construction 15 of parts and their combination, as hereinafter specified, whereby strength and facility and accuracy of adjustment are obtained.

In the accompanying drawings, Figure 1 is a side elevation. Fig. 2 is a central longitudinal section, showing the construction and 20 arrangement of the parts by means of which the required adjustments are obtained.

Similar letters of reference indicate similar parts in both figures.

A is a handle, having the ferrule B. The 25 shaft D is secured permanently to the handle A. The shaft D is provided with ratchet-teeth D' D" on each side. The teeth on the opposite sides of the shaft D are at different heights, not occupying the same plane at 30 the respective sides. The lower or sliding jaw is shown by a and the fixed jaw by a'. The sliding jaw a forms a part of the sliding shank C, which exteriorly is of cylindrical shape, and fits neatly within the ferrule B. The shank 35 C has a longitudinal aperture of square or

rectangular cross-section, neatly fitting the shaft D, so as to slide thereon. E E are pawls pivoted at e to the shank C, and are kept in engagement with the ratchet-teeth by the springs F. The pawls are made to engage 40 one or more teeth.

The operation of the wrench will be readily understood. When the lower jaw, a, is to be shifted, the pawls E are pressed against the springs and disengaged from the ratchet-teeth D' D', and the jaw moved by hand. 45

This wrench, in its construction, possesses simplicity and strength, and is easily manipulated to the nicest adjustments.

Having described my invention, I claim— 50

1. The combination, in a monkey-wrench, of a ferrule, cylindrical sliding shank carrying the lower movable jaw, spring-pawls, and stationary shaft carrying the fixed jaw, and having serrations at each side, substantially 55 as set forth.

2. In a wrench, a cylindrical shank carrying the movable jaw, and a stationary shaft carrying the fixed jaw, said shaft passing longitudinally through the shank, combined with a 60 stationary ferrule and handle, the ferrule being constructed to receive and guide the shank, substantially as set forth.

In testimony whereof I have hereunto set my hand and seal this 15th day of October, 65 A. D. 1883.

JAMES HOULEHAN. [L. S.]
